RALPH N. RICHARDS, OF TOLEDO, OHIO, ASSIGNOR TO OTTAWA RIVER PAPER COMPANY, OF TOLEDO, OHIO, A CORPORATION OF OHIO

COMBINATION SHIPPING CASE AND DISPLAY STAND

Application filed December 11, 1931. Serial No. 580,270.

This invention relates to an improved combination shipping case and display stand adapted to be made from stiff paper or similar sheet material.

5 The great majority of shipping cases now used are made of paper and after being used once are of no practical value, except in occasional instances where they may be used for reshipping.

10 It is the object of the present invention to provide a shipping case which is especially adapted to be used as a floor display stand after a shipment has been removed therefrom.

15 The present embodiment of the invention will be more particularly described in connection with the accompanying drawing, in which—

Figure 1 represents a blank from which 20 the shipping case is made.

Figure 2 is a perspective view of a shipping case partially completed.

Figure 3 is a perspective view of the shipping case after it has been closed and sealed.

25 Figure 4 is a perspective view of a shipping case after the end is cut off preparatory to converting the case into a display stand.

Figure 5 is a perspective view of the same case folded to form a display stand, but before the insert has been placed therein.

Figure 6 is a perspective view of an insert used to complete the display stand.

Figure 7 is a perspective view of the completed display stand.

35 Figure 8 is a perspective view of an insert which may be used instead of that shown in Fig. 6.

In accordance with my invention a blank of the required size is cut, as shown in Figure 1. This blank comprises panels 10, 11, 40 12 and 13 with score lines 14 about which they are folded to form the four sides of a box. As shown in Fig. 2, the adjacent edges of the panels 10 and 13 are usually bound

45 together by cambric tape or other suitable material, as indicated at 15, to meet railroad classifications for shipping containers. The blank is also provided with end flaps 16 and score lines 17 about which they may be folded to form the top of the case, as shown in

Fig. 3. Bottom flaps 18 are also provided with score lines 19 about which they may be folded to form the bottom of the case. The flaps 16 and 18 are separated by corner slots 20 preparatory to folding. 55

When a shipment has been received in the shipping case, the top 21 should be carefully removed by cutting along the dot and dash line 22, which may be marked on the outside of the container, if desired. 60

In order that the shipping case may be especially adapted to be converted into a floor display stand, fold lines 23, 24 and 25 are scored on the inside of the panels 11, 12 and 13, respectively, before the blank is folded. 65

In order to facilitate the conversion the panel 12 is also provided with diagonal score lines 26 extending from the ends of the fold line 24 to the center of the fold line 17. After the top 21 has been removed, as indicated in Figure 4, and the contents of the case taken out, the upper portion of the panel 12 may be folded inwardly across the case, as shown at 27 in Fig. 5, to form a horizontal seat for receiving articles for display. The upper part 75 of the rear side of the case then serves as a back for the seat, as indicated at 28, while the sides are doubled about the lines 23 and 25 to a triangular shape, as shown at 29 and 30. 80

In order that the display stand thus formed may retain its shape and also have an attractive finished appearance, an insert may be furnished with each shipping case. As shown in Fig. 6, this insert comprises two 85 panels 31 and 32 which may be folded about the line 33 and which have a force fit between the sides 29 and 30. Thus, when the insert is placed in the top of the display stand, it is held therein by friction. 90

If preferred, an insert consisting of a single panel, as indicated at 34 in Fig. 8, may be provided instead of the insert shown in Figs. 6 and 7.

The combination shipping case and display stand may be manufactured at substantially the same cost as an ordinary shipping case. The only change necessary is to provide the additional score lines 23, 24, 25 and 26 and to furnish a suitable insert which 100

may be packed within the case when goods are shipped. When the case, after being used for a shipment of goods, is converted into a floor display stand, it presents a very 5 noticeable and attractive appearance, particularly if the sides of the case and the insert are printed with attractive designs. This printing may be done merely by adding a printing unit to the cutting and scoring 10 machines where the blank is made. The use of such a combination shipping case and display stand offers a substantial inducement for a buyer to purchase his goods from a firm which uses this style of case.

15 If it is desired to manufacture a floor display stand which is not to be used first as a shipping case, the blank is originally cut as above described, except that the flaps 16 are omitted. This blank is then folded in the 20 same manner as shown in Fig. 5.

While I have shown and described the invention in detail, it is understood that it includes all such modifications as may fall within the scope of the appended claims.

25 What is claimed is:

1. A combination shipping case and display stand having top, bottom, front, rear and side walls, a score line extending transversely across the front wall, and score lines 30 in the side walls extending upwardly and rearwardly from the ends of said transverse score line to the edges of the rear wall, whereby the upper portion of the front wall may be folded rearwardly and the upper 35 front portions of the side walls folded against the inside faces of said side walls to form a display stand seat, after the top of the case is removed.

2. A combination shipping case and display stand having top, bottom, front, rear and side walls, a score line extending transversely across the front wall, and score lines in the side walls extending upwardly and rearwardly from the ends of said transverse 45 score line to the edges of the rear wall, whereby the upper portion of the front wall may be folded rearwardly and the upper front portions of the side walls folded against the inside faces of said side walls to 50 form a display stand seat, after the top of the case is removed, said front wall also having score lines extending from the ends of said transverse score line diagonally to the upper edge of said front wall to facilitate the folding.

3. A combination shipping case and display stand having top, bottom, front, rear and side walls, a score line extending transversely across the front wall, and score lines 60 in the side walls extending upwardly and rearwardly from the ends of said transverse score line to the edges of the rear wall, whereby the upper portion of the front wall may be folded rearwardly and the upper front 65 portions of the side walls folded against the

inside faces of said side walls to form a display stand seat, after the top of the case is removed, and an insert having a force fit in said seat and adapted to be inserted therein to reinforce and retain the folded portions 70 in their folded positions.

4. A combination shipping case and display stand having top, bottom, front, rear and side walls, a score line extending transversely across the front wall, and score lines in the side walls extending upwardly and rearwardly from the ends of said transverse score line to the edges of the rear wall, whereby the upper portion of the front wall may be folded rearwardly and the upper front 75 portions of the side walls folded against the inside faces of said side walls to form a display stand seat, after the top of the case is removed, said front wall also having score lines extending from the ends of said transverse score line diagonally to the upper edge of said front wall to facilitate the folding, and an insert having a force fit in said seat and adapted to be inserted therein to reinforce and retain the folded portions 80 in their folded positions.

5. A display stand made from stiff sheet material and having front, rear, and side walls, a score line extending transversely across the front wall, and score lines in the side walls extending upwardly and rearwardly from the ends of said transverse score line to the edges of the rear wall, whereby the upper portion of the front wall may be folded rearwardly and the upper front 85 portions of the side walls folded against the inside faces of said side walls so that the entire upper edges of the side walls are in supporting relation to the rearwardly folded portion of the front wall to constitute a display stand seat.

6. A display stand made from stiff material and having front, rear, and side walls, a score line extending transversely across the front wall, and score lines in the side walls extending upwardly and rearwardly from the ends of said transverse score line to the edges of the rear wall, whereby the upper portion of the front wall may be folded rearwardly and the upper front portions of the side walls folded against the inside faces of said side walls so that the entire upper edges of the side walls are in supporting relation to the rearwardly folded portion of the front wall to constitute a display stand seat, said front wall also having score lines extending from the ends of said transverse score line diagonally to the upper edge of said front wall to facilitate the folding.

7. A display stand having front, rear and side walls, a score line extending transversely across the front wall, and score lines in the side walls extending upwardly and rearwardly from the ends of said transverse score line to the edges of the rear wall, where-

- by the upper portion of the front wall may be folded rearwardly and the upper front portions of the side walls folded against the inside faces of said side walls to support the rearwardly folded portion of the front wall in position to constitute a display stand seat, and an insert having a force fit in said seat and adapted to be inserted therein to reinforce and retain the folded portions in their folded positions. 5
8. A display stand having front, rear, and side walls, a score line extending transversely across the front wall, and score lines in the side walls extending upwardly and rearwardly from the ends of said transverse score line to the edges of the rear wall, whereby the upper portion of the front wall may be folded rearwardly and the upper front portions of the side walls folded against the inside faces of said side walls to support the rearwardly folded portion of the front wall in position to constitute a display stand seat, said front wall also having score lines extending from the ends of said transverse score line diagonally to the upper edge of said front wall to facilitate the folding, and an insert having a force fit in said seat and adapted to be inserted therein to reinforce and retain the folded portions in their folded positions. 10
9. A display stand made from stiff sheet material and having front, rear and side walls, a score line extending transversely across the front wall, and score lines in the side walls extending upwardly and rearwardly from the ends of said transverse score line, the remaining portions of the side walls being unscored whereby the upper portion of the front wall may be folded rearwardly and the upper front portions of the side walls folded against the inside faces of said side walls to form a display stand seat, the ends of the seat being thus supported by the folded-in sections of the side walls. 15
10. A display stand made from stiff sheet material and having front, rear and side walls, a score line extending transversely across the front wall, and score lines in the side walls extending upwardly and rearwardly from the ends of said transverse score line, the remaining portions of the side walls being unscored whereby the upper portion of the front wall may be folded rearwardly and the upper front portions of the side walls folded against the inside faces of said side walls to form a display stand seat, the ends of the seat being thus supported by the folded-in sections of the side walls, said front wall also having score lines extending from the ends of said transverse score lines diagonally to the upper edge of said front wall to facilitate the folding. 20
11. A display stand made from stiff sheet material and having front, rear and side walls, a score line extending transversely across the front wall, score lines in the side walls extending upwardly and rearwardly from the end of said transverse score line, whereby the upper portion of the front wall may be folded rearwardly and the upper front portions of the side walls folded against the inside faces of said side walls to support the same in position to constitute a display stand seat, and means for engaging and holding in shape the folded-in portion. 25
12. A display stand made from stiff sheet material and having front, rear and side walls, a score line extending transversely across the front wall, score lines in the side walls extending upwardly and rearwardly from the end of said transverse score line, whereby the upper portion of the front wall may be folded rearwardly and the upper front portions of the side walls folded against the inside faces of said side walls to support the same in position to constitute a display stand seat, said front wall also having score lines extending from the ends of said transverse score lines diagonally to the upper edge of said front wall to facilitate the folding, and means for engaging and holding in shape the seat portion. 30
- In testimony whereof I have hereunto signed my name to this specification.
- RALPH N. RICHARDS. 35
